UNITED STATES PATENT OFFICE.

THOMAS YOUNG, OF ENFIELD, ENGLAND.

SOUND AMPLIFIER.

Application filed December 24, 1925, Serial No. 77,558, and in Great Britain December 30, 1924.

This invention relates to improvements in sound amplifiers of trumpet shape.

Broadly, my invention relates to sound amplifiers of trumpet shape, which may be used in apparatus for the emission and for the reception of sound. For the purpose of this specification, a "trumpet" may be defined as a tube whose bore gradually increases from one end to the other, and whose axis may be either straight or curved in any of the forms well known in connection with wind musical instruments.

The object of the invention is the provision of an improved amplifier for amplifying sounds emitted by gramophones, radio loud speakers, and the like, or the provision of an improved sound receiver for use in telephony either by cable or wireless, whereby the tone quality of the original sound shall be preserved.

The invention consists in a sound amplifier comprising a plurality of frusta of hollow cones made of laminated wood, joined together preferably in such manner as to ensure as far as possible continuity in direction of the grain of the wood from end to end of the trumpet.

The invention further consists in a sound amplifier as defined in the preceding paragraph in which the various frusta are each made by overlapping winding or coiling and gluing or otherwise fastening together a plurality of flat strips of wood of suitable length and shape.

The invention further consists in a sound amplifier as defined in the two preceding paragraphs in which the frusta at a bend of the trumpet are first made all integral with the contiguous straight conical part or parts of the trumpet, are cut therefrom, and the whole of the parts are then joined together.

The invention also consists in a sound amplifier as defined in the preceding paragraphs, comprising a plurality of parts rotatably joined together, the axis of a joint being coincident or tangential to the axis of the trumpet at that place. By the use of such joints the flare or mouth of a trumpet or horn may be set in any desired direction which may be chosen as that best adapted to receive or

emit the sound to be transmitted, while preserving the acoustical continuity of the column of air within the trumpet.

According to the invention, the tone-arm of a gramophone is made in two parts, one part a right angle bend, and the other part the tone-arm proper, the said two parts being rotatably jointed together, and the other end of the bend being rotatably jointed to the cabinet or other part in fixed relation to the table or cabinet of the gramophone. Further, the tone-arm and horn of a gramophone are made as one continuous trumpet comprising parts rotatably jointed together.

Drawings are appended illustrating a few forms in which my invention may be carried into effect.

Figures 1 and 2 diagrammatically illustrate my invention applied to the tone arm and horn of a gramophone, Figure 1 being an elevation and Figure 2 a plan.

Figures 3-5 are views showing the details of the joints of a jointed trumpet or horn.

Figures 6-8 are diagrams illustrating one method of making the parts of a trumpet.

Figure 9 is a view of a spiral or snail trumpet with a continuous surface which can be approximated to by means of my invention by using a fairly large number of frusta per complete turn of the spiral.

In Figure 1 is shown a horn comprising a conical stem A¹, a bend made up of conical frusta B¹, B², B³, B⁴, a conical part A² and a conical mouth or flare C. In one method, the parts A¹, B¹, B², B³, B⁴ and A² are cut from a straight conical tube A as shown in elevation in Figure 6, by plane saw-cuts 2 oblique to the axis 1-1 of the cone. If the two frusta divided by such a saw slit be reversed relative to each other and joined together they will fit exactly. The axes of the two frusta are now no longer in line but are inclined at an angle to each other, where X is the angle which the normal to the plane of the cut makes with the axis of the cone. For a plain right angle bend as in Figure 1, the saw-cuts in Figure 6 are preferably all at the same angle X, and oppositely inclined to the axis of the cone. The four frusta necessitate 5 saw cuts, and as the axis 1-1, of the bend 100

Figure 6 is bent at an angle at each of the five joints: the angle X is therefore 9 degrees. The frusta B^1 , B^2 , B^3 , B^4 are preferably all similar. The axial length of a 5 frustum, being chosen to correspond with the desired mean radius of curvature at the start of the bend, that of the others is determined by a well known geometrical method, such as by drawing the series of similar 10 triangles indicated by the dotted lines. A right angle bend may comprise any convenient number of frusta. With three frusta involving four joints the angle X is 11.25 degrees: with two frusta the angle X is 15 15 degrees. The greater the number of frusta the more closely does the axis of the bend approximate to a logarithmic spiral, and its inner and outer surfaces approximate to continuous surfaces.

20 Theoretically, the width of the saw-cuts 2 implies that the contiguous edges of the parts A^1 , B^1 , B^2 , B^3 , B^4 and A^2 when assembled as shown in Figure 1 do not exactly fit; but in practice, the saw-cuts are so thin that the 25 deviation from perfect fit of the joints is practically negligible.

The said parts may of course be each made independently, their edges being trimmed so as to secure exact fit when assembled, but 30 this process of manufacture is more tedious.

The bend 4 and tone-arm 5 of a gramophone (Figures 1 and 2) are made in the same manner as described with reference to the trumpet parts A^1 , B^1 , B^2 , B^3 , B^4 , A^2 .

35 A spiral or "snail" trumpet bend can be made in a somewhat similar manner as follows:—The end A^2 of the tube A (Figure 3) being held in a lathe, after cutting off the part A^1 , the tube A is rotated through a suitable small angle before cutting off the frustum B^1 : and so on, the tube being rotated 40 after cutting off each frustum. A snail trumpet made with 24 segments per complete turn approximates fairly closely to a continuous 45 surface trumpet, as in Figure 9 which shows a continuous snail trumpet of one and a quarter turns.

The tube A (Figure 6) is made by coiling 50 two or more layers of thin wood on a mandrel. Figure 7 shows the development of two layers a^1 and a^2 . Each layer may comprise two or more pieces arranged as shown. The various pieces are cut so that their long 55 edges when coiled round the mandrel are inclined to the straight lines which can be drawn on the surface of the conical mandrel.

Figure 8 shows the development of the flare or mouth C of the trumpet (Figure 1). Each layer is shown as made up of six segments 60 and the run of the grain is indicated in two adjacent pieces of the layer a^2 . The greater the number of segments the less is the break in continuity of direction of the grain in passing from segment to segment.

65 The small end of the tube A^1 and the ends

of the bend 4 and tone arm 5 are provided with metal ferrules 7 and 8, the ferrule 8 at the small bore end of the tone arm being slotted at 9 to receive the sound box of the gramophone. The ferrules 7 in Figure 3 are 70 adapted to form ball-races for a ball bearing. Figure 3 is a section of the joint at 10 between the bend 4 and tone arm 5.

Figure 4 is a section of the joint at 11 in which the ferrule 7 attached to trumpet A^1 75 is screwed in fixed relationship to a base plate 12 which is fastened by screws or the like to the gramophone cabinet or table T, the bend 4 being rotatable relative to said plate. The trumpet is thus attached to the cabinet only at its small bore end, its mouth being presented to the opening at the door D, but is not fixed there in any way. It is otherwise not constrained and is free to vibrate without any damping action as is the case 80 when additional support is provided.

Figure 5 is a modification of the joint at 11, which permits the trumpet to be rotated relative to the base plate 12, in cases where the base or frame of the instrument permits. 90 These joints each comprise a double thrust ball-race 14, the assemblage being completed by an outer ball-race ring 15 screwed to the other outer ball race 16. In Figure 5, an additional plain bearing is provided, the ball-race 16 being rotatable relative to the base plate 12 and secured in position by a ring 17 screwed to the base plate. A spring washer 18 may be inserted between the base plate 12 95 and ball race 16, exerting pressure between the various parts of the joint. The mouth C of the trumpet A can be set in any desired direction horizontally, and the friction of the joint will tend to keep it in position, until appreciable effort is exerted to change its 100 position.

I find that sound amplifiers or trumpets made of wood according to my invention 105 when applied in connection with gramophones and loud speakers for wireless telephony reproduce more faithfully than has been the case hitherto the essential characteristics of the original sound. Probably this is due to the fact that the higher overtones, which constitute the equality or "timbre" peculiar to an individual voice, musical instrument, orchestra or chorus, are not modified or suppressed, while the trumpet does 110 not introduce any new overtones due to its own construction.

I claim:—

1. A sound amplifier comprising a plurality of laminated, wood, hollow conical frusta, having their base edges joined together, the wood grain of the entire amplifier 115 running in a direction substantially lengthwise of the amplifier.

2. A method of making a sound amplifier which consists in making a hollow conical tube of laminated wood, cutting said tube 120

into several frusta, reversing certain frusta from their cut out position, and securing together the base edges of the several frusta so that the axis of one frusta makes an angle 5 with the axis of another frusta.

3. A tone-arm for a gramophone in which the neck is rotatably jointed to the casing and

the tone-arm proper is rotatably jointed to said neck and each comprise a plurality of laminated wood hollow conical frusta having their base edges cemented together. 10

In testimony whereof, I affix my signature.

THOMAS YOUNG.
